(57) **CLAIM**

The ornamental design for a indoor/outdoor ultrasonic bark controller, as shown and described.

DESCRIPTION

FIG. 1 is a right front perspective view of an indoor/outdoor ultrasonic bark controller showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The structural elements depicted by broken lines has been shown for the purpose of illustrating portions of the indoor/outdoor ultrasonic bark controller that form no part of the claimed design.
